(57) **CLAIM**

I claim the ornamental design for an articulated MRI device, as shown and described.

DESCRIPTION

FIG. 1 is a perspective view of an articulated MRI device, showing my new design with a clamshell imaging head in an open position;

FIG. 2 is a right-side elevational view of FIG. 1, the left-side elevational view being a mirror image thereof;

FIG. 3 is a front elevational view of FIG. 1;

FIG. 4 is a rear elevational view of FIG. 1;

FIG. 5 is a top plan view of FIG. 1;

FIG. 6 is a bottom plan view of FIG. 1; and,

FIG. 7 is a perspective view thereof, showing the clamshell imaging head in a closed position.
